UNITED STATES PATENT OFFICE.

KATE E. BROYLES, OF SACRAMENTO, CALIFORNIA.

DESIGN FOR A CHRISTMAS-TREE ORNAMENT.

Application filed May 5, 1926. Serial No. 17,576. Term of patent $3\frac{1}{2}$ years.

To all whom it may concern:

Be it known that I, KATE E. BROYLES, a citizen of the United States, residing at Sacramento, in the county of Sacramento and State of California, have invented a new, original, and ornamental Design for a Christmas-Tree Ornament, of which the following is a specification, reference being had to the accompanying drawing, forming part thereof, which shows a front elevation of a Christmas-tree ornament showing my new design.

The crescent is wrapped with gold and silver cord to simulate a fleecy cloud effect.

I claim:

The ornamental design for a Christmas tree ornament, as shown and described.

Mrs. KATE E. BROYLES.
